UNITED STATES PATENT OFFICE.

MARTIN R. FREEBERG, OF MINNEAPOLIS, MINNESOTA.

CLOTHES-LINE CLAMP.

1,249,371.

Specification of Letters Patent. Patented Dec. 11, 1917.

Application filed January 26, 1916. Serial No. 74,445.

To all whom it may concern:

Be it known that I, MARTIN R. FREEBERG, a citizen of the United States, residing at Minneapolis, in the county of Hennepin 5 and State of Minnesota, have invented new and useful Improvements in Clothes-Line Clamps, of which the following is a specification.

This invention relates to clothes line 10 clamps, and it has for its object to produce a clamp of simple and improved construction by means of which a clothes line or the like may be tightened and securely clamped or held in position for use.

15 A further object of the invention is to produce a clamp of the character described, the body of which may be easily and inexpensively manufactured of sheet metal by properly bending and manipulating the 20 same.

With these and other ends in view which will readily appear as the nature of the invention is better understood, the same consists in the improved construction and novel 25 arrangement and combination of parts which will be hereinafter fully described and particularly pointed out in the claims.

In the accompanying drawing has been 30 illustrated a simple and preferred form of the invention, it being, however, understood that no limitation is necessarily made to the precise structural details therein exhibited, but that changes, alterations and modifications within the scope of the claims may be 35 resorted to when desired.

In the drawing,—

Figure 1 is a top plan view of a clamp constructed in accordance with the invention.

40 Fig. 2 is a front end view of the same.

Fig. 3 is a side elevation.

Fig. 4 is a rear end view.

Fig. 5 is a longitudinal sectional view taken on the line 5—5 in Fig. 1.

45 Fig. 6 is a perspective view illustrating the operation of the device.

Corresponding parts in the several figures are denoted by like characters of reference.

50 The improved clamping device comprises a bottom plate or base plate 15 of substantially rectangular shape having at one side an upturned flange 16, said flange being provided at the ends thereof with laterally ex-

tending hooks 17. Notches 18 are formed 55 in the base plate 15 adjacent to the ends of the upstanding flange 16. Riveted or otherwise secured on the base plate 15 is a cleat 19 and a flat spring 20, the latter being positioned beneath one of the arms of the 60 cleat.

In operation, the clothes line, indicated at 21, is engaged with a support, such as a post 22, it being understood that one end of said line has been previously attached 65 to some fixed supporting point, indicated at 23. An intermediate portion of the line is laid in the angle between the base plate 15 and the flange 16, portions thereof being engaged with the notches 18 and looped 70 around the shanks of the hooks 17, the clamping device being thereby held in adjusted position on the line, but in such a manner that it may be very readily detached or its position changed. The free end of 75 the line having been brought around or otherwise engaged with the post or supporting member 22 is now connected with the cleat 19, the free end being finally passed beneath the retaining spring 20. It will be 80 readily understood that by pulling upon the line, the latter may be properly tensioned, it being secured by the clamping device.

Having thus described the invention, what is claimed as new, is:—

85

1. A line clamp comprising a base plate having an upturned flange provided with laterally extending terminal hooks for slideable and frictional engagement with an intermediate portion of a line, and a cleat 90 mounted on the base plate for adjustable engagement with a terminal portion of the same line.

2. A device of the class described comprising a base plate having an upstanding 95 flange provided with laterally extending end members and notches adjacent to the ends of said flange, and a line attaching device on said base plate, said line attaching device consisting of a cleat and a flat spring positioned between the base plate and one arm of the cleat.

100

In testimony whereof I affix my signature in presence of two witnesses.

MARTIN R. FREEBERG.
